PUMPING ARRANGEMENT

Frank J. Sigmund and William S. Hlavin, Cleveland, Ohio, assignors, by mesne assignments, to Sigmund Corporation, a corporation of Ohio

Application December 29, 1941, Serial No. 424,702

3 Claims. (Cl. 103—113)

Our invention relates in general to a pumping arrangement and more particularly to a pumping unit comprising a main pump and an auxiliary pump capable of expelling air from the main pump, together with a control circuit for causing the auxiliary pump to be operated when no liquid is being pumped by the main pump and to cause the auxiliary pump to be inactive when liquid is being pumped by the main pump.

When a liquid pump becomes "air bound," it fails to deliver water or liquid through the discharge outlet thereof. A pump may become "air bound" by the draining of the pump resulting from the leakage of the strainer in the suction pipe. Air may also enter the pump through other avenues to destroy the proper functioning of the pump. When a pump is "air bound" the water or liquid, if any, is merely circulated within the pump impeller chamber.

An object of our invention is the provision of an auxiliary pump which is capable of expelling air from the main pump when the main pump becomes "air bound."

Another object of our invention is the provision of operating the auxiliary pump so long as the main pump does not deliver or pump liquid and to arrest the operation of the auxiliary pump when the main pump begins to pump liquid through the discharge outlet thereof.

Another object of our invention is to accomplish the control for governing the operation of the auxiliary pump by means of a light-sensitive device responsive to the presence or absence of the liquid being pumped through the discharge outlet of the main pump.

Another object of our invention is to accomplish the control of the auxiliary pump by means of a pressure responsive switch which is responsive to the liquid in the discharge outlet of the main pump.

Another object of our invention is the provision of driving the auxiliary pump by means of a magnetic clutch from the main shaft of the main pump wherein the magnetic clutch is energized to drive the auxiliary pump when no liquid is being pumped out of the discharge outlet of the main pump and to deenergize the magnetic clutch when liquid begins to flow out through the discharge outlet of the main pump.

Other objects and a fuller understanding of our invention may be had by referring to the following description and claims, taken in conjunction with the accompanying drawing, in which:

Figure 1 is a view in side elevation of a pump-

ing unit embodying the features of our invention, part of the pumping unit being shown in section to illustrate more clearly the working parts thereof; and

5 Figure 2 is a diagrammatic illustration of a modified form of our invention.

With reference to Figure 1 of the drawing, the combined pump assembly is illustrated generally by the reference character 10 and comprises a main pump indicated by the reference character 11 and an auxiliary pump indicated by the reference character 12. As illustrated, the main pump and the auxiliary pump are combined in one complete assembly. Between the main pump 11 and the auxiliary pump 12 there is an inlet chamber 14 into which liquid or water flows through the inlet pipe 13 which may lead downwardly to a well or sump or other body of liquid which is to be pumped. Branching off from the inlet chamber 14 is an inlet 15 for the main pump 11. The outlet for the main pump is designated by the reference character 16. In operation of the main pump, liquid flows from the inlet chamber 14 through the inlet 15 to the impeller 19 which is driven by the shaft 24 after which the discharged liquid flows out through the outlet 16. The inlet for the auxiliary pump is indicated by the reference character 17 and the outlet by the reference character 18. The impeller 20 for the auxiliary pump is adapted to closely fit within the involute chamber of the auxiliary pump and is capable of expelling air from the main pump 11. In other words, the auxiliary pump 12 may be characterized as a self priming pump. The impeller 20 for the auxiliary pump may comprise a plurality of substantially radially extending vanes or blades which revolve within an involute chamber having relatively close fitting sides. The action of the pump impeller 20 is such that when it is rotated it has the property of expelling the air from the inlet chamber 14 and from the main pump 11.

45 The impeller 19 of the main pump is mounted directly upon the shaft 24 of the pump assembly. The shaft 24 may be driven by a prime mover indicated by the reference character 25 and may comprise either an electric motor or Diesel engine or any other type of motive power suitable for the purpose. The shaft 24 extends from one 50 one of the pump assembly to the other and as illustrated upon the left-hand side of the pump assembly there is provided a magnetic clutch 26 comprising an outside engaging disc 27 and an inside engaging disc 28. The outside engaging disc 27 is non-rotatably connected to the shaft

24 so that it rotates continuously with the rotation of the shaft 24. The inside engaging disc 28 is carried by a sleeve 31 which is also connected to the impeller 20 of the auxiliary pump. The sleeve 31 immediately to the right of the inside engaging disc 28 is supported by a hollow bearing member 33 and the right-hand end of the sleeve 31 or the impeller 20 is arranged to be supported around a bearing 32 carried by the shaft 24. Accordingly, the rotation of the inside engaging disc 28 operates to drive the impeller 20 for the auxiliary pump 12. Although the outside engaging disc 27 is non-rotatively connected to the shaft 24, yet it may slide longitudinally relative to the shaft 24 under the action of magnetic flux set up by magnetic windings 34 provided in the inside engaging disc 28. A spring 30 is provided around the shaft 24 and is arranged to engage the end of a sleeve 29 for urging the outside engaging disc 27 of the magnetic clutch away from the inside engaging disc 28. Consequently, when the magnetic clutch 26 is de-energized the auxiliary pump 12 is idle. The magnetic winding 34 for the magnetic clutch is arranged to be energized through contact rings 35 and 36 respectively engaged by electrical brushes 37 and 38. The contact rings 35 and 36 are suitably insulated from the inside engaging disc 28 and the electrical brushes 37 and 38 are constrained to slide against the contact rings 35 and 36 by means of suitable springs positioned in the rear of the electrical brushes 37 and 38.

The liquid or water upon leaving the main pump 11 flows upwardly through the outlet 16 thereof and then upwardly through an outlet pipe 41 to the source of delivery. Mounted within the outlet pipe 41 is a pivot valve 42 having a lower flange portion 47 anchored between two flanges 43 and 44 which connect the outlet pipe 41 to the outlet 16 for the main pump. The two flanges 43 and 44 may be held together by suitable screw bolts 45. A gasket 46 is provided between the two flanges 43 and 44 to prevent leakage through the mating surfaces of the two flanges 43 and 44 and also to prevent leakage around the flange portion 47 of the pivot valve 42. In this manner, liquid which is entrapped above the pivot valve 42 is prevented from leaking back into the main pump 11.

The electrical control which governs the operation of the auxiliary pump 12 is controlled by a light source indicated generally by the reference character 49 and a photoelectric cell 50. The light rays which emanate from the light source 49 pass through windows 48 mounted upon opposite sides of the outlet pipe 41 before falling upon the photoelectric cell 50. The windows 48 may be of any suitable construction so long as liquid is prevented from leaking therefrom and so long as the light rays from the light source 49 may pass therethrough and fall upon the photoelectric cell 50. The feeble current which is developed within the photoelectric cell 50 is carried to an amplifying and relay equipment 53 which may be of any suitable design and structure. The conductors 54 carry the feeble current developed by the photoelectric cell 50 to the amplifying and relay equipment 53, which is energized from an electric power current source 51 upon the closing of a switch 52. The light source 49 may be energized by the power current source through conductors 55. The magnetic clutch 26 is energized by the amplifying and relay equipment 53 through conductors 56 that are electrically connected to

the electrical brushes 37 and 38 of the magnetic clutch.

The outlet 18 for the auxiliary pump is likewise covered by the electrical control arrangement through a slide valve 59 actuated by an electro-magnet 58. A spring 60 within the slide valve is adapted to bias the slide valve to the right and close the communication of the outlet for the auxiliary pump to atmosphere. Energization of the electro-magnet 58 through the conductors 57 forces the slide valve to the left as shown in the drawing until the transverse opening therethrough registers with the outlet 18 for the auxiliary pump, under which condition the outlet 18 for the auxiliary pump is connected to atmosphere.

In operation, let it be assumed that the switch 52 is closed and that the amplifying and relay equipment 53, together with the other electrical control parts, is energized. Under this assumption, let it be further assumed that the main pump 11 is delivering no liquid or water out of the outlet 16. Under this condition, the light from the light source 49 will pass through the windows 48 and fall upon the photo-electric cell 50. The current developed by the photo-electric cell will cause the amplifying and relay equipment 53 to operate to magnetize the winding 34 of the magnetic flux. The engagement effected by the magnetic clutch will drive the auxiliary impeller 20 from the shaft 24. The operation of the auxiliary pump 12 expels air from the inlet chamber 14 and from the main pump 11. The expelling of air from the main pump enables the main pump now to pump liquid or water through the outlet 16 and raise the pivot valve 42. The flow of liquid or water past the pivot valve 42 causes the valve to swing about its hinge and intercept the light falling upon the photo-electric cell 50. The interception of the light from the photo-electric cell 50 causes the relay and amplifying equipment 53 to cut off the current from the magnetic clutch 26, in which event the auxiliary pump 12 is disconnected from the shaft 24. The main pump 11 continues to operate to pump liquid while the auxiliary pump 12 remains idle. The operation will continue so long as liquid is being pumped by the main pump 11.

Should the main pump 11 become air bound or fail to deliver water through the outlet 16, the pivot valve 42 then swings downwardly and allows the light rays from the light source 49 to fall upon the photo-electric cell 50, whereupon the magnetic clutch 26 is again energized for operating the auxiliary pump to expel air from the main pump 11. The advantage of arresting the operation of the auxiliary pump 12 when the main pump 11 is pumping liquid is that it prevents the auxiliary pump from wearing out as it might do if it were run continuously. The continuous running of the auxiliary pump is disadvantageous particularly when the water or liquid contains fine sand or other grit-like particles. The impeller 20 for the auxiliary pump fits relatively close to the side walls of the pump involute chamber so that the action of the fine sand and other grit-like particles would tend to wear a relatively large clearance between the impeller blades and the side walls of the pump involute. This would tend to decrease the efficiency of the auxiliary pump if allowed to run continuously while the main pump is operating.

So long as the auxiliary pump 12 is in opera-

tion, it expels air through the outlet 18 past the slide valve 59 which is opened by the electro-magnet 58 when the magnetic clutch is magnetized. Just as soon as the magnetic clutch is de-magnetized, the spring 60 biases the slide valve to the right as shown in the drawing and blanks off the auxiliary pump outlet 18 from atmosphere so that no air may be drawn in through the auxiliary pump to the main pump 11.

In Figure 2 is shown a diagrammatic illustration of a modified form of our invention, in that we employ a pressure switch indicated generally by the reference character 64 to control the energization of the magnetic clutch and the electro-magnet 58. As illustrated, the pressure switch 64 comprises a flexible tube 65 and a mercury switch 66. The magnetic clutch 26 and the electro-magnet 58 are energized through conductors 67. In operation, when the fluid or liquid is being pumped by the main pump 11, the pressure within the outlet pipe 41 causes the flexible tube 65 to actuate the mercury switch and de-energize the magnetic clutch and the electro-magnet 58. Should the main pump 11 fail to deliver liquid through the outlet pipe 41 in which case there would be no liquid pressure within the outlet pipe 41, the flexible tube 65 actuates the mercury switch such that the magnetic clutch 26 and the electro-magnet 58 are energized to cause the auxiliary pump 12 to expel the air from the main pump 11. The auxiliary pump 12 continues to operate until the air is expelled from the main pump 11 at which time the main pump again begins to deliver liquid through the outlet pipe 41 and operate the mercury switch 66 to de-energize the magnetic clutch and close the slide valve 59.

In both of the embodiments shown in our invention, we provide for arresting the operation of the auxiliary pump so long as the main pump is delivering liquid and to start the operation of the auxiliary pump 12 when the main pump becomes air bound or fails to deliver liquid out of the discharge outlet 18.

Although we have described our invention with a certain degree of particularity, it is understood that the present disclosure has been made by way of example and that numerous changes in the details of construction and the combination and arrangement of parts may be resorted to without departing from the spirit and the scope of the invention as hereinafter claimed.

What is claimed is as follows:

- 5 10. In combination, a main pump, a priming pump, and light-sensitive means responsive to the liquid in the outlet of the main pump for controlling the priming pump, said light sensitive means causing operation of the priming pump to expel air from the main pump so long as substantially no liquid is being pumped by the main pump and arresting the operation of the priming pump when liquid is being pumped by the main pump.
- 15 20. In combination, a main pump, a priming pump, movable means responsive to the movement of the liquid in the outlet of the main pump, and light-sensitive means responsive to the movement of the movable means for controlling the priming pump, said light-sensitive means causing operation of the priming pump to expel air from the main pump so long as substantially no liquid is being pumped by the main pump and arresting the operation of the priming pump when liquid is being pumped by the main pump.
- 25 30. In combination, a first pump, a second pump, and light sensitive means responsive to the liquid in the outlet of the first pump for controlling the second pump, said light sensitive means causing operation of the second pump so long as substantially no liquid is being pumped by the first pump and arresting the operation of the second pump when liquid is being pumped by the first pump.
- 35 40. In combination, a first pump, a second pump, and light sensitive means responsive to the liquid in the outlet of the first pump for controlling the second pump, said light sensitive means causing operation of the second pump so long as substantially no liquid is being pumped by the first pump and arresting the operation of the second pump when liquid is being pumped by the first pump.
